UNITED STATES PATENT OFFICE

HAROLD C. HARVEY, OF TRENTON, NEW JERSEY, ASSIGNOR TO THE AGASOTE MILL-BOARD COMPANY, OF TRENTON, NEW JERSEY, A CORPORATION OF NEW JERSEY

APPARATUS FOR MAKING PULP BOARD

Application filed August 26, 1931. Serial No. 559,361.

The present invention relates to a machine for manufacturing pulp board and similar articles. The particular object of my invention is to provide an apparatus from which the molded pulp board or similar article can readily be removed with as little disturbance as possible to the soft article. More particularly, my apparatus is an improvement upon the type of apparatus disclosed in United States Letters Patent No. 1,536,163 issued May 5, 1925 upon an invention of D. M. Sutherland, Jr.

Sheets of paper pulp, wood pulp, or the like, and particularly thick, large sheets of this material, are made by placing a suitable quantity of pulp into a mold consisting of a bottom, a top and a frame constituting a deckle. After the pulp has been placed into the mold the top of the mold is pressed upon the surface of the pulp to expel the bulk of the liquid therefrom, such liquid passing through the bottom of the mold and possibly also through the top of the mold, such bottom, or bottom and top, being suitably constructed to permit passage of the liquid, while preventing passage of the fibres. Molds such as referred to are shown in patent to Sutherland et al. No. 971,936 dated October 4, 1910, in patent to Sutherland No. 1,272,566 dated July 16, 1918 and in patent to Sutherland No. 1,536,163.

The soft sheet of pulp must then be removed from the mold in order to be carried to the drier and this may be done in various ways. In the structure disclosed in the Sutherland Patent No. 1,536,163, of which the present invention is an improvement, a conveyor is provided between the deckle and the mold bottom, the pulp sheet is formed on such conveyor, and after completion is removed by such conveyor after the deckle has been raised sufficiently to afford clearance for the molded pulp.

The principle and objects of my invention may best be understood from the description of an apparatus embodying the same. Such an apparatus is shown by way of example, but not by way of limitation, in the accompanying drawing in which

pulp mold and associated parts showing the mold in closed position and the mold top in contact with the top of the completely formed sheet of molded pulp; and

Fig. 2 is a similar section showing the mold 55 open and the molded pulp board ready for removal.

The central feature of the apparatus is a mold. This may be constructed in the manner shown in the drawing in which 5 represents a channeled mold bed or bottom provided with apertures such as channels 6 to constitute drainage passages through which water may run off as it drains or is pressed through the pulp; gutters 7 may also be provided to catch such water as flows from the side of the mold bed.

The mold bed is provided also with a foraminous screen 8, which, in a manner well known in the art, permits water to drain therethrough without permitting the passage of pulp fibres. As will hereinafter be explained, this screen forms the means or a part of the means for withdrawing the sheet of wet pulp from the mold. The mold bed 65 may be supported in a variety of ways as will be explained hereinafter.

The deckle 9 may be constructed in any suitable manner, for instance as described in the Patent No. 1,536,163 hereinabove referred to, and may be provided with suitable inlets (shown in dotted lines) as shown and described in such patent for the purpose of permitting an introduction of the pulp supplied into the mold.

The mold top 10 is arranged to fit slidably within the deckle, being preferably surrounded by said deckle permanently as and for the reasons described in said Patent No. 1,536,163.

The mold top and deckle are arranged to permit relative movement. The deckle may be fixed and the mold top movable or the mold top may be fixed and the deckle movable. In the particular construction shown, the mold top is suspended from and firmly attached to the fixed head 11 by means of a web or webs, for instance, by webs 12, and the deckle is provided with means supported by such fixed head for raising and lowering

Fig. 1 is a sectional front elevation of a

the same. For instance, the means for raising and lowering the deckle may consist of cylinders 13, pistons 14 and piston rods 15, and suitable conduits 16 and 17 for permitting the inflow or escape of a fluid pressure medium. The fixed head 11 is slidably supported on the plurality of standards 18 which also support the cross-head 19, actuated by a hydraulic ram 20. The crosshead 19 carries on each side a bracket 21, each carrying rollers 22, 23 and 24 and also a roller 25 carried at the end of an adjustable bolt 26. The conveyor, apron, or foraminous screen 8 is in the form of an endless belt encircling the mold bed 5 and passes over rollers 22, 23 and 24, and is held in taut position by the roller 25 and adjustable bolt 26. Driving arrangements may be attached to the rollers 22 to facilitate the movement of the apron 8. The upper face of the crosshead 19 is provided with bosses 27 between pairs of which the apron 8 is adapted to pass and the upper surfaces of which are adapted to contact with the lower surface of the mold bottom 5 as shown in Fig. 1.

On the top of the crosshead 19, below the portion of the conveyor which lies below the mold bottom, and between pairs of the bosses 27, is placed a rubber blanket 28 of a thickness between three-quarters of an inch and one and one-half inches, depending upon the frequency with which such blanket is subjected to pressure, and the amount of such pressure. The thicker the blanket, the less would be its elongation under the frequent and continued pressure to which it is subjected.

In order to prevent the metallic surface of the deckle 9 from injuring the delicate fabric of the fine, woven wire constituting the apron 8, wherever such surface may come in contact with the moving wire, I provide a soft rubber strip 29 on the surface of the deckle along such parts thereof which come in contact with the moving wire.

The mold bottom 5 is shown as supported by links 30 from the deckle 9 in such manner that the deckle may be raised for a distance sufficient to clear the molded pulp. The mold bottom is not raised, but as the deckle is further raised, it carries the mold bottom with it so as to permit the portion of the apron 8, lying between the mold bottom and the crosshead, to move freely and out of contact with the mold bottom.

It will be noted that by means of the structure just outlined, I make possible the passing of the continuous screen or apron 8 through the mold press, the return portion of the apron passing through an intermediate platen or mold bed supported from the deckle so as to provide an open space between said mold bed and deckle when the board is not being pressed. When the press is closed, and the board is under pressure,

the intermediate platen or mold bed is closed and becomes a part of the main adjacent platen or mold top. The intermediate platen thus provides an opening through which the return section of the endless belt passes through the press without such section of the belt coming in contact with the surface of the section of the belt in contact with the board. By providing this method of return through the press itself instead of over the top of the mold bed or underneath the crosshead, a considerable saving in the construction costs of the press is effected.

A further feature of the improved apparatus is the provision of a cushion which is in contact with the wire whenever the wire itself and the platens are under pressure. In my improved construction, both sections of the wire constituting the endless belt or apron are always in contact with a cushion, one layer being the pulp sheet and the other layer being the rubber blanket, thereby avoiding the friction and great wear which has been found to exist, due to the indented surfaces of the two wires rubbing together when being moved in reverse directions to each other, which rubbing of the indented surfaces greatly damages the delicate fabric of the finely woven wire.

While I have described a particular embodiment of my invention, it is obvious that various changes therein, particularly in the arrangement of the parts, may be made without departing from my invention. Thus the particular means shown and described of supporting the intermediate platen from the deckle is intended for illustrative purposes only as it is obvious that various means of suspending such platen from the deckle will occur to those skilled in the art.

I claim:

1. An apparatus of the character described, having in combination a crosshead, a mold top, and a mold bed, each movable relatively to the other, a foraminous conveyor located between said mold top and said crosshead and having its sections separated by said mold bed and in contact with the upper surface thereof, and a deckle surrounding said mold top.

2. An apparatus as claimed in claim 1 in which the mold bed is supported from the deckle in such manner that the deckle may be raised for a distance sufficient to clear the molded pulp and further raised to carry the mold bed with it so as to permit the portion of the conveyor lying between the mold bed and the crosshead to move freely and out of contact with said mold bed.

3. An apparatus as claimed in claim 1 having a blanket of a resilient material, such as a rubber composition or the like, on the top of the crosshead and below the portion of the conveyor which lies below the mold bed.

HAROLD C. HARVEY.
